UNITED STATES PATENT OFFICE

HUGH F. ELLIOTT, OF ST. LOUIS COUNTY, MISSOURI, ASSIGNOR TO INTERNATIONAL SHOE COMPANY, OF ST. LOUIS, MISSOURI, A CORPORATION OF DELAWARE

TOE BOX FOR BOOTS OR SHOES

Application filed May 22, 1929. Serial No. 364,991.

This invention relates to boots or shoes and has special reference to the toe portions thereof, and an object is to provide a boot or shoe having embedded or enclosed within the toe portion thereof, that is to say, confined between the toe cap and the toe portion of the shoe upper, a device or means that functions as a heat insulator so as to protect the toes of the wearer from becoming burned, and which is combined with a strong and yet yielding or resilient member to protect the toes of the wearer from being injured by heavy weights dropping on the toes of the shoes, etc.

The present invention comprises a novel device or means enclosed or confined between the toe cap and the toe portion of the shoe upper for obtaining the desirable results or effects of protecting the toes of the wearer from becoming burned when the shoes are near or in contact with heated objects or materials, and also to protect the toes of the wearers from injury resulting from striking against solid objects or articles, or from dropping heavy objects on the toes.

Other objects will appear from the following description, reference being made to the drawings in which—

Fig. 1 is a plan view of the toe portion of a shoe having my invention embodied therein, a part of the toe cap being broken away to show my improved guard.

Fig. 2 is a vertical longitudinal sectional view approximately on the line 2—2 of Fig. 1.

Fig. 3 is a vertical cross sectional view approximately on the line 3—3 of Fig. 1.

Fig. 4 is a plan view of one form of the device that is interposed between the toe cap and the toe portion of the shoe upper to obtain the advantages of this invention.

Fig. 5 is a cross sectional view approximately on the line 5—5 of Fig. 4.

Fig. 6 is a plan view of the toe portion of a shoe upper having another form of the invention embodied therein, a part of the cap being broken away.

Fig. 7 is a vertical longitudinal sectional view approximately on the line 7—7 of Fig. 6.

Fig. 8 is a vertical cross sectional view approximately on the line 8—8 of Fig. 6.

Fig. 9 is a plan view of an alternative form of the device from that shown in Fig. 4.

Fig. 10 is a cross sectional view approximately on the line 10—10 of Fig. 9.

The present invention comprises a device, 55 preferably such as that shown, including a section 1 of woven wire or wire screening enclosed and confined and secured or embedded between two similarly shaped sections or plies of flexible and pliable material. As shown, 60 these sections of flexible and pliable material include a section 2 at one side of the screen 1 and a section 3 at the other side of the screen 1. One or the other or both of the sections 2 and 3 may be a rubberized composition or 65 other material or substance capable of being vulcanized so that when subjected to heat it will penetrate thoroughly and fill the interstices of the screen 1 and, when cooled, will resume a satisfactory pliable, non-liquid 70 form.

Against one of the plies, in the present instance, the plies 3, a ply 4 of asbestos or other non-combustible heat resisting substance or material is secured. This ply 4 75 may be attached to the remaining structure by wire fasteners 5 forced through said ply 4 and the remaining structure and clinched, or by other appropriate attaching devices.

This device is bent and shaped to fill up 80 the toe portion of the shoe upper 6 so as to enclose and shield and guard said toe portion; the lower marginal edge 7 (Figs. 2 and 3), which is the curved edge 8 (Fig. 4) being close to or engaged by the fastening means 85 9 whereby the shoe upper is attached to the sole.

In this arrangement the ply 4 is on the upper side of the device. The toe cap 10 is applied to enclose and confine this guard and has its lower marginal edge secured between the upper and the sole, and its upper and rear marginal edge attached to the shoe upper by rows of stitching 11. The rows of stitching 11 are beyond the rear edge of the 95 guard device that is interposed between the cap 10 and the toe portion of the shoe upper, while the edge 8 having abutting or engaging contact with the rigid part of the shoe construction adjacent to the fasteners 9, is se- 100

curely held. Moreover, when this device is bent to shape it will retain the shape in which it is bent. For, although characterized by a certain degree of resiliency, the wires of the screen 1 are strained so as to effect a molecular change sufficient to cause the device to retain the desired shape and formation for application upon the toe portion of the shoe upper.

In the variation of the device shown in Figs. 6 to 9 inclusive, the guard or shield comprises a section 12 of woven wire or wire screening. Against one side of the screen 12 a section 13 of appropriate pliable material is laid. The opposite side of the screen 13 is covered by a section 14 having the characteristics of the section 4, that is to say, the section 14 is non-combustible and is heat resisting. Upon the section 14 a section 15 of pliable material is laid and these parts are fastened or secured together by appropriate means such as the wire fasteners 16 passing through said parts and being clinched.

This device is bent and shaped to fill up the toe portion of the shoe upper 17, the lower marginal edge 18 (Figs. 7 and 8) which is the covered edge 19 (Fig. 9) abutting against a rigid part of the shoe structure and being close to or engaged by the fasteners 20 whereby the shoe upper is attached to the sole. In this arrangement the asbestos section 14 is above the screen 12. On this device the toe cap 21 is positioned having its lower marginal edge secured between the upper and the sole and its upper and rear marginal edge attached to the shoe upper by rows of stitching 22. The rows of stitching 22 are beyond the rear edge of the guard device that is interposed between the cap 21 and the toe portion of the shoe upper 17, while the edge 19 abuts against a rigid part of the shoe structure and has abutting or engaging contact with the fasteners 20 and is securely held. This device will retain its shape and, although characterized by a desirable degree of resiliency, the wires of the screen 12 are strained so as to effect a molecular change sufficient to cause the device to retain the desired shape and formation for its intended purpose.

The device may be otherwise varied within equivalent limits without departing from the nature and principle characterizing the invention.

I do not restrict myself in any unessential respects but what I claim and desire to secure by Letters Patent is:

1. In a boot or shoe, a shoe upper, a toe box covering the toe portion of the shoe upper and comprising a metallic section, a flexible substance seated upon the toe portion of the shoe upper and covering the inner side of said metallic section, a non-combustible substance between said metallic section and the toe cap, and a toe cap covering said toe box and having its rear edge attached to the shoe up-

per rearwardly of the upper edge of said toe box.

2. In a boot or shoe, an upper, a toe box covering the toe portion of the upper and comprising a section of reticulated metallic material having its lower edge adjacent to the shoe sole and its upper edge extending across the shoe upper, a flexible substance between said section of reticulated material and the shoe upper, a toe cap having its rear edge attached to the shoe upper rearwardly of the upper edge of said toe box and having its lower edge attached to the shoe sole, and a ply of non-metallic, non-combustible heat resisting substance between said reticulated material and said toe cap.

3. In a boot or shoe, an upper, a toe box covering the toe portion of the upper and comprising a section of reticulated metallic material having its lower edge adjacent to the shoe sole and its upper edge extending across the shoe upper, a toe cap having its rear edge attached to the shoe upper rearwardly of the upper edge of said section of reticulated material and having its lower edge attached to the shoe sole, and a ply of flexible, non-combustible heat insulating material between said section of reticulated material and said toe cap.

4. In a boot or shoe, an upper, a toe box covering the toe portion of the upper and comprising a section of reticulated metallic material having its lower edge adjacent to the shoe sole and its upper edge extending across the shoe upper member, a toe cap member having its rear edge attached to the shoe upper member rearwardly of the upper edge of said section of reticulated material and having its lower edge attached to the shoe sole, and a section of non-combustible heat insulating material between said reticulated material and one of said members.

5. In a boot or shoe, an upper, a toe box covering the toe portion of the upper and comprising a section of reticulated metallic material having its lower edge adjacent to the shoe sole and its upper edge extending across the shoe upper member, and a flexible substance embedding said reticulated section and comprising a ply of heat insulating non-combustible material.

6. In a boot or shoe, an upper, a toe box covering the toe portion of the upper and comprising a section of reticulated metallic material having its lower edge adjacent to the shoe sole and its upper edge extending across the shoe upper member, a flexible substance embedding said reticulated section and comprising a ply of heat insulating non-combustible material, and a toe cap covering said toe box and having its rear edge attached to the shoe upper rearwardly of the upper edge of said section.

7. In a boot or shoe, comprising a shoe upper and a toe cap having its rear edge at-

tached to said upper and its lower edge attached to the shoe sole, the combination therewith of a toe box covering the toe portion of the upper and composed of a ply of heat insulating non-combustible material enclosed between the toe cap and the shoe upper, and a metallic member arched and curved to the shape of the toe portion of the shoe upper and also enclosed between said toe cap and the shoe upper.

5 8. In a boot or shoe, comprising a shoe upper and a toe cap having its rear edge attached to said upper and its lower edge attached to the shoe sole, the combination therewith of a toe box covering the toe portion of the upper and composed of a ply of heat insulating non-combustible material enclosed between the toe cap and the shoe upper, a metallic member arched and curved to the
15 shape of the toe portion of the shoe upper and also enclosed between said toe cap and the shoe upper, and means fastening said ply of heat insulating material to said metallic member.
